CLAIM

The ornamental design for a compressor wheel as shown and described.

DESCRIPTION

FIG. 1 is a top plan view of the compressor wheel in accordance with one embodiment of the present invention; FIG. 2 is an elevational side view, which is identical to the front and rear views, of the compressor wheel in FIG. 1; FIG. 3 is a bottom plan view of the compressor wheel in FIG. 1; and,

FIG. 4 is a top perspective view of a compressor wheel in FIG. 1.

The broken lines shown in the drawings depict portions of the compressor wheel which form no part of the claimed design.
